UNITED STATES PATENT OFFICE.

FRANK CECIL SCHLITZER, OF BUFFALO, NEW YORK, ASSIGNOR TO THE BEAVER COMPANY, A CORPORATION OF OHIO.

SAMPLE CONTAINER.

Application filed October 30, 1920. Serial No. 420,589.

To all whom it may concern:

Be it known that I, FRANK CECIL SCHLITZER, a citizen of the United States, residing at Buffalo, in the county of Erie, 5 State of New York, have invented certain new and useful Improvements in Sample Containers; and I do hereby declare the following to be a full, clear, and exact description of the invention, such as will enable 10 others skilled in the art to which it appertains to make and use the same.

My invention is an improvement in containers for beaver board samples and in blanks for forming said containers and the 15 invention has for its object to provide a simple inexpensive device of the character specified, in the form of a strip of paper or the like, so creased that it may be folded about a sample of beaver board in two directions at right angles to each other thereby to completely enclose the sample, and to provide a tuck fold for receiving the ends of the strip to prevent disengagement of the 20 said ends and to permit the ends to be sealed to the tuck fold.

In the drawings:-

Fig. 1 is a plan view of the completed container.

Figs. 2 and 3 are sections on the lines 2—2 30 and 3—3 of Fig. 1.

Fig. 4 is a plan view of the strip creased and ready to fold.

Fig. 5 is a similar view showing the sample of beaver board in place.

Figs. 6 to 11 inclusive are views showing the various steps of folding.

In the present embodiment of the invention the improved container or enclosure is formed from a strip 1 of suitable material, 40 as for instance, paper of suitable weight, and this paper is creased on double lines, indicated at 2, in such a manner as to form five folds of substantially the same area, and it will be understood that the strip 1 is of 45 a width corresponding approximately to one dimension of the sample which it is to contain.

Five folds are provided, a central fold and four lateral folds, and the central fold is creased on a line 3 which is diagonal to the fold, and to the strip.

In order to make use of the container or enclosure, the strip is folded on the line 3, the right end of the strip being folded up-

ward and the line 3 is so directed that the 55 upfolded end of the strip will be at right angles to the other end. Now the beaver board indicated at 4, preferably in an envelope 5 which may or may not have a sealing flap 6 is laid upon that lateral fold of 60 the horizontal end of the strip which is adjacent to the central fold.

The strip is now folded on the line which separates the central fold from that lateral fold upon which is laid the beaver board 65 sample and the entire strip is folded over upon the beaver board sample as shown in Fig. 7. That lateral fold which is adjacent to the central fold and on the opposite side of the central fold from the beaver board sample is then folded down upon the central fold as shown in Fig. 8. When this is done the two end folds will extend one to the left of the beaver board sample and one below. These two folds are now folded up 70 and tucked beneath the diagonal fold which forms a tuck for holding the said ends. That is the said ends are folded upwardly upon the front of the beaver board sample and their corners are tucked beneath the 75 tuck as clearly shown in Figs. 9 and 10. They may be secured in place if desired by a seal indicated at 6, and the seal being placed half on the tuck fold and half on the topmost end of the strip.

The arrangement is such, and the strip or blank is so creased, that by folding on the central diagonal creased line, the two ends of the strip will extend at right angles to each other and may be folded about the 80 sample board in directions at right angles to each other, thereby to completely enclose the sample and to provide a tuck fold for engaging the ends of the sample.

The sample board, to be enclosed in the 85 container, may be a square of composite roofing, or roofing felt, or other like product.

I claim—

1. A wrapper for a body having rectangular faces, comprising a strip of material 100 of a width corresponding to that of a face of the body and being creased intermediate its ends along a diagonal line arranged to place the portions of said strip at right angles to each other when said strip is folded along said crease; said portions being of sufficient length to pass around the body in directions at right angles and to provide 105

ends to be tucked beneath the fold provided on one face of the body by the folding of the strip along said diagonal line.

2. An envelope for square enclosures, 5 comprising a strip of a width corresponding approximately to that of the enclosure, and having intermediate its ends a diagonal crease line spaced at its center from one end of the strip a distance corresponding 10 substantially to two and one-half times the width of the strip, whereby when the strip is folded on the crease line to cause the ends to lie at substantially a right angle, and the other end is folded about an enclosure, the 15 fold at the crease line will form a tuck for engagement by the extremity of the first named end when it in turn is folded about the enclosure.

3. An enclosure for sample boards, comprising a strip creased transversely to form 20 a central and four lateral folds of approximately the same area as the sample, the strip being creased diagonally of the central fold whereby when it is folded on said diagonal creased line the ends will extend at 25 right angles to each other and may be folded about the sample and tucked beneath the tuck fold formed by the folding on the diagonal line.

- 30 4. An envelope comprising a strip creased intermediate its ends on a line extending at an angle of 45° to the axis of the strip, and spaced at its center from one end of the strip a distance corresponding to two and 35 one-half times the width of the strip, whereby when the strip is folded on the crease line, and the other end is wrapped about a square having a width substantially that of the strip, the first named end of the strip 40 will fold over the square and the first named end at right angles to the direction of fold of the said first named end and the extremity thereof will be received in the tuck formed by the first named fold.

- 45 5. An enclosure for board samples, comprising a strip of a width corresponding to one dimension of the sample and creased on transverse lines at intervals corresponding approximately to the other dimension of the 50 sample, to form a central and two lateral

folds at each side of the central fold, the strip being creased diagonally of the central fold whereby when the strip is folded on the diagonal line and then over upon the adjacent lateral fold a tuck fold will be 55 formed for the ends of the strip.

6. A blank for containers for sample boards, comprising a strip creased transversely at regular intervals to form five approximately equal folds, the strip being creased diagonally to the central fold, the width of the strip corresponding approximately to one dimension of the sample and the first named creased lines being separated by intervals corresponding approximately 60 to the other width of the sample.

7. An envelope comprising a strip having transverse crease lines spaced apart from one end of the strip and from each other a distance equal to the width of the strip, to 70 provide five or more similar folds, and having a crease line extending diagonally of the third fold from one end, whereby when the strip is folded on the crease line to cause the ends to lie at substantially a right angle, 75 and the other end is folded about an enclosure, the fold at the crease line will form a tuck for engagement by the extremity of the first named end when it in turn is folded about the enclosure.

8. A wrapper for a body having rectangular faces comprising a strip of material creased intermediate its ends along a diagonal line to enable said strip to be folded readily to place the portions of said strip 80 opposite the fold at right angles to each other; said portions being of a length respectively to wrap entirely around the body in the respective directions in which they extend when the part of said strip having the fold is placed on one face of said body with the fold running diagonally of the face and the portions extending at right angles to adjacent edges of said face,—said folded portion being then arranged to permit the 85 ends of the respective portions to be tucked beneath it.

In testimony whereof I affix my signature.

FRANK CECIL SCHLITZER.

Certificate of Correction:

It is hereby certified that Letters Patent No. 1,457,551, granted June 5, 1923, upon the application of Frank Cecil Schlitzer, of Buffalo, New York, for an improvement in "Sample Containers," were erroneously issued to "The Beaver Company, a Corporation of Ohio, whereas said Letters Patent should have been issued to *The Beaver Products Company, Inc., a Corporation of New York*, said corporation being assignee, by *meuse assignments*, of the entire interest in said invention, as shown by the records of assignments in this office; and that the said Letters Patent should be read with these corrections therein that the same may conform to the record of the case in the Patent Office.

Signed and sealed this 17th day of July, A. D., 1923.

[SEAL.]

WM. A. KINNAN,
Acting Commissioner of Patents.
